FOLDABLE METAL AWNING

Nicholas L. Etten, Cedar Falls, Iowa

Application July 11, 1951, Serial No. 236,259

10 Claims. (Cl. 160—58)

1

This invention relates to a foldable metal awning and operating means therefor.

Conventional foldable awnings of the past have suffered from numerous disadvantages. In particular those constructed of canvas and the like have been generally quite flimsy in construction and are highly susceptible to damage by wind and the elements.

An object of this invention is to provide an improved awning of a strong and durable metal construction.

Another object of this invention is to provide improved operating means for a foldable awning.

A further object of this invention is to provide an improved awning readily constructed of metal and smoothly and easily actuatable between retracted and extended positions.

Still another object of this invention is to provide an improved foldable metal awning so constructed as to be self-locking in both retracted and extended positions.

A still further object of this invention is to provide a foldable awning with improved operating means whereby it can be quickly and easily extended.

According to this invention, the awning includes a plurality of hinge-connected lowered panel sections actuatable from compact folded positions to extended positions. Pivotal side panels are connected to the top panel sections so as to be actuated therewith and are so disposed as to offer support for the extended top panels as well as to prevent entry of rain or the like from the sides. The hinge connections of the top panels are so related that the top panels are in over-center locking relation in the extended positions thereof while the weight of the panels themselves maintains them in superimposed relation in the retracted positions thereof.

The outer extended top panel section has a valance section hinged thereto and rope and pulley operating means act on the valance section to retract or fold the awning.

The valance section in its initial retracting movement engages the outer extended top panel section to move it out of its over-center locked position. The awning can be quickly extended, the rope being so connected that only a small movement is necessary to move the parts from the folded positions thereof to a position where the weight of the parts themselves will carry them to the extended positions thereof.

Other objects, features and advantages of the present invention will become more fully ap-

2

parent from the following detailed description taken in conjunction with the accompanying drawings which illustrate a preferred embodiment of the invention and in which:

Figure 1 is a perspective view of an awning constructed according to this invention mounted on a window frame and in extended position;

Figure 2 is a perspective view of the awning of Figure 1 in retracted or folded position;

Figure 3 is a side elevational view of the awning of Figure 1 with the parts in the relative positions thereof just after the start of the retracting movement;

Figure 4 is a side elevational view of the awning showing the relative positions of the parts at a further stage of the retracting movement;

Figure 5 is a side elevational view of an upper portion of the awning with the top panel sections in folded positions, the retracting movement having been completed;

Figure 6 is a sectional view taken substantially along line VI—VI of Figure 1;

Figure 7 is a front elevational view illustrating the rope and pulley operating means for the awning, the top panels and sides being shown in phantom for clarity of illustration; and

Figure 8 is a sectional view, on an enlarged scale, taken substantially along line VIII—VIII of Figure 1.

In general, an awning constructed according to this invention may include an upper louvered top panel or canopy section 20 arranged to be affixed to and extend outwardly and downwardly from the upper portion of a window or door frame. A pair of triangulate side panels 21 and 22 have upper edge portions thereof secured to the top panels 20. Inturned flanges at the rear vertical edges of the side panels 21 and 22 may be secured to the side members of the window or door frame.

An intermediate louvered top panel section 23 is hinged by means of pins 24 to the lower and outer edge portion of the upper fixed top panel 20 and an outer louvered top panel section 25 is hinged by pins 26 to the intermediate section 23. The top panel sections 23 and 25 may thus be folded into superimposed relation over the fixed top panel section 20 as illustrated in Figures 2 and 5 or may be actuated to the extended positions illustrated in Figures 1 and 6. The movement of the top panel sections 23 and 25 will be clear from reference to Figures 3 and 4 which show the sections in intermediate positions.

To guide the sections 23 and 25 in their movement between folded and extended positions, a pair of arms 27 are pivoted by pins 28 to lower

portions of the fixed side panels 21 and 22 and are pivotally secured to the outer top panel section 25.

A plurality of side panels are arranged to be movable from retracted positions in nested relationship with the fixed side panels 21 and 22 to extended positions in which they are so disposed as to offer support for the extended top panels as well as to prevent entry of rain and the like from the side. These include a pair of intermediate triangulate side panels 29 and 30 and a pair of outer triangulate panels 31 and 32 each pivotally secured to the associated one of the fixed side panels 21 and 22 by means of pins 32a.

The movable side panels 29, 30, and 31 and 32 are connected together for concurrent movement. For this purpose, a horizontal hollow shaft 33 is journaled for rotation between the fixed side panels 21 and 22 and below the fixed top panel section 20. A pair of lever arms 34 are secured to the shaft 33, an intermediate point on each lever arm 34 being connected through a link or arm 35 to the associated one of the intermediate side panels 29 and 30 and an outer point of each lever arm 34 being connected through a link or arm 36 to the associated one of the outer side panels 31 and 32.

A unique and advantageous arrangement is provided for actuation of the movable parts of the awning from the extended positions thereof to the folded positions thereof. This arrangement includes a valance section 38 which is hinged to the outer top panel section 25 by pins 39. Rope and pulley means are arranged to act on this valance section 38 to retract the awning. Lost-motion connections are provided between the valance section 38 and the side panels 31 and 32 including a pair of arcuate slots 40 (Figure 6) in the outer side panels 31 and 32; headed studs 41 affixed to the valance section 38 are engaged in these arcuate slots 40.

The advantages of the lost-motion connections and of other structures described above will be made clear hereinafter in a detailed description of the operation of the awning, but a clear understanding of the rope and pulley arrangement will be advantageous in considering the operation as a whole and will now be described.

Referring to Figures 6, 7 and 8, a pair of pulleys 42 and 43 are rotatably secured to the valance section 38 and three pulleys 44, 45 and 46 are mounted beneath the fixed top panel section 20. A rope 47 is secured at one end to the shaft 33 and extends downwardly to the valance section 38, about the pulley 42, upwardly over the shaft 33, around the pulley 44, over to and around pulley 45, downwardly over the shaft 33 to the valance 38, around the pulley 43, upwardly over the shaft 33, around the pulley 46, downwardly to a looped portion with the other end of the rope 47 being secured to the right-hand link 36, viewed in Figure 6, adjacent the pivotal connection of the link 36 to the arm 34. The looped portion of the rope 47 forms actuating portions 47a and 47b which may be selectively pulled downwardly manually to retract or extend the awning.

Retraction

It will be seen that when the awning is extended as illustrated in Figures 1 and 6, the axis of hinge pins 26 is below a line through the axis of hinge pins 24 and the axis of pivotal connection of the arms 27 to the outer to panel section 25 so that the movable top panel sections 23 and 25 are effectively locked in an over-

center relation. When the portion 47a of the rope 47 is pulled downwardly, the rope will act inwardly on the valance-section pulleys 42 and 43, and the valance section 38 and the outer top panel section 25 will pivot as a unit about the axis of pivotal connection of the arm 27 to the top panel section 25. The position of the parts just after this initial retracting movement has taken place is illustrated in Figure 3. It will be noted that, as shown in Figure 3, the parts have been moved out of over-center locking position with the axis of pin 26 above a line through the axis of pin 24 and the axis of pivotal connections of the arms 27 with the top panel section 25. Thus the parts that have been locked in over-center relation in the extended position thereof will be moved out of the locking relation in the initial retracting actuation of the rope 47.

Further downward movement of the portion 47a of the rope will move the parts through the position of Figure 4 to the fully retracted position as shown in Figures 2 and 5. It will be noted that the side panels are retracted through the engagement of studs 41 on the valance section 38 in the slots 40 in the side panels 31 and 32. The lost-motion connection provided by studs 41 and the slots 40 prevents locking and binding of the parts in their movement between retracted and extended positions.

Extension

To actuate the movable parts of the awning from the retracted position thereof illustrated in Figures 2 and 5 to the extended position, the portion 47b of the rope is pulled downwardly which will rotate the lever arm 34 counter-clockwise, as viewed in Figure 5, to force the movable side panels outwardly by means of links 35, 36. The outer side panels 31 and 32 will actuate the valance section 38 outwardly through the engagement of studs 41 in slots 40 and the valance section 38, in turn, moves the top panel sections 23 and 25 about the axis of hinge pins 24 until a position is reached where the weight of the top panel sections and side panel sections is sufficient to carry them on out to the extended position thereof. Thus only a comparatively small movement of the portion 47b of the rope is required to extend the awning.

Having thus described the construction and operation of the awning in general, the construction and assembly of the component parts of the awning of this invention will be described in detail.

The upper fixed top panel section 20 includes a pair of facing allochiral channels 51 and 52 between which a plurality of louvers are secured. The channels 51 and 52 are secured to inturned flanges at the upper edges of fixed side panels 21 and 22 as by rivets. An upper or watershed louver 53, Figure 6, is secured at each end below the upper legs or flanges of the channels 51 and 52 and has a downturned flange 53a which may be secured to the upper member of a window or door frame, as by screws.

A plurality of louvers 54 are secured in overlapping relation between the side panels 51 and 52. For this purpose, the side panels 51 and 52 have integrally formed attachment ears 55 and 56 to which the louvers 54 are riveted or otherwise affixed.

The pulley blocks 44, 45 and 46 may be affixed to members 57 which are mounted below the watershed louver 53. The ends of the shaft 33

are journaled in bearing plates 53 secured to the side channels 51 and 52.

The intermediate top panel section 23 includes a pair of allochiral side channels 59 and 60 and a plurality of louvers 61 affixed therebetween. The side channels 59 and 60 are preferably provided with integral tabs 62 and 63 to which the louvers 61 are riveted or otherwise secured. To hinge the top panel section 23 to the fixed top panel section 20, the side channels 51 and 52 of the fixed top panel section 20 and the side channels 59 and 60 of the intermediate top panel section 23 are preferably formed with integral loops forming bearings for the hinge pins 24.

The outer top panel section 25 includes a pair of allochiral side channels 65 and 66 each having integral mounting tabs 67 and 68 to which end portions of a plurality of louvers 69 are riveted or otherwise affixed. To hinge the top panel section 25 to the top panel section 23, the side channels 59 and 60 of the top panel section 23 and the side channels 65 and 66 of the top panel section 25 may be formed with integral loops forming bearings for the hinge pins 26. The pivotal connection between the arms 27 and the top panel section are likewise provided by integral loops 71 on the side channels 65 and 66 which provide bearings in which transversely extending terminal end portions of the arms 27 are journaled.

The valance section 38 includes a pair of allochiral side brackets 73 and 74 each having a generally L-shaped cross-section and a valance plate 75 extending between and affixed to the brackets 73 and 74. The brackets 73 and 74 have integral loop portions aligned with integral loop portions of the side channels 65 and 66 of the top panel section 25 to provide bearings for the hinge pins 39.

The pulleys 42 and 43 are rotatably supported on a pair of brackets 76 and 77, respectively (Figures 6 and 8), which are secured to the side brackets 73 and 74, respectively, of the valance section 38. The studs 41, which extend through the slots 40 in the side panels 31 and 32, are threaded into internally threaded openings in the pulley support brackets 76 and 77.

In summary, the awning of this invention is assembled from readily formed metal parts to provide a strong and durable construction attractive in appearance. The movable components of the awning lock in over-center relation in the extended positions thereof but may be readily actuated by the rope and pulley arrangement into folded positions. The awning may be quickly and easily extended since the rope need be pulled downwardly only a comparatively small distance to actuate the panels to positions where they are carried by their own weight to the extend locked positions thereof.

It will be understood that modifications and variations may be effected without departing from the spirit and scope of the novel concepts of the present invention.

I claim as my invention:

1. An awning comprising a plurality of hinge-connected top panel sections extendable from folded relation to extended over-center locked relation, and retracting means acting on the outermost top panel section and initially moving said sections out of said over-center locked relation.

2. An awning comprising a plurality of hinge-connected top panel sections foldable from extended relation into gravity-locked superimposed relation, and extending means actuatable to move

said panel sections out of said superimposed relation to positions in which they are gravity-impelled to extended positions.

3. An awning comprising a plurality of hinge-connected top panel sections movable between folded positions in gravity-locked superimposed relation and extended positions in over-center locked relation, retracting means acting on the outermost top panel section and initially moving said sections out of said over-center locked relation, and extending means actuatable to move said panel sections out of said superimposed relation to positions in which they are gravity-impelled to said extended positions.

4. An awning comprising a plurality of hinge-connected top panel sections extendable from folded relation to over-center locked relation, and rope and pulley means retracting on the outermost top panel section and initially moving said sections out of said over-center locked relation.

5. An awning comprising a plurality of hinge-connected top panel sections movable between folded positions in gravity-locked superimposed relation and extended position in over-center locked positions, rope and pulley retracting means acting on the outermost top panel section and initially moving said sections out of said over-center locked relation, and extending means actuatable to move said panel sections out of said superimposed relation to positions in which they are gravity-impelled to said extended positions.

6. An awning comprising a downwardly inclined fixed top panel section, a first movable top panel section hinged to said fixed top panel section, a second movable top panel section hinged to said first movable top panel section, and a guide and support arm pivoted at one end thereof to said second movable section and pivoted at the other end thereof for movement about a fixed axis spaced below said fixed top panel section, said movable panels being actuatable from folded positions in superimposed gravity-locked relation over said fixed top panel section to extended positions generally in alignment with said fixed top panel section and in over-center locked relation.

7. An awning comprising a downwardly inclined fixed top panel section, a first movable top panel section hinged to said fixed top panel section, a second movable top panel section hinged to said first movable top panel section, and a guide and support arm pivoted at one end thereof to said second movable section and pivoted at the other end thereof for movement about a fixed axis spaced below said fixed top panel section, said movable panels being actuatable from folded positions in superimposed gravity-locked relation about said fixed top panel section to extended positions generally in alignment with said fixed top panel sections in which the axis of the hinge connection of said first and second movable top panel section is spaced below a line through the axis of the hinged connection of said first movable section to said fixed section and the axis of pivotal connection of said guide arm to said second section, whereby said sections are locked in over-center relation.

8. An awning comprising a downwardly inclined fixed top panel section, a first movable top panel section hinged to said fixed top panel section, a second movable top panel section hinged to said first movable top panel section, a guide and support arm pivoted at one end

thereof to said second movable section and pivoted at the other end thereof for movement about a fixed axis spaced below said fixed panel section, said movable panels being actuatable from folded positions in stacked gravity-locked relation above said fixed top panel section to extended positions generally in alignment with said fixed top panel section and in over-center locked relation, a valance section connected to said second movable top panel section, and rope and pulley retracting means acting on said valance section to pivot the same and said second movable top panel section about the axis of the pivotal connection between said arm and said second movable section and thereby out of over-center locked relation.

9. An awning comprising a downwardly inclined fixed top panel section, a first movable top panel section hinged to said fixed top panel section, a second movable top panel section hinged to said first movable top panel section, said movable panels being foldable from extended relation into gravity-locked superimposed relation over said fixed sections, and awning extending means for actuating said movable sections out of folded relation to positions in which they are gravity-impelled to extended positions.

15

20

25

10. An awning comprising a plurality of hinge connected top panel sections foldable from extended positions into gravity-locked superimposed relation, a pair of side panel assemblies each including a plurality of side panels movable fan-like from positions in nested relation to extended position in supporting relation to said top panel sections, means connecting said side panel assemblies and said top panels for concurrent movement, and awning extending means acting on said side panels and actuatable to move said top panel sections out of said gravity-locked superimposed relation to positions in which they are gravity-impelled to extended positions.

NICHOLAS L. ETTEL.
